(74) Attorney, Agent, or Firm—Starkweather & Associates; Michael W. Starkweather; Jason P. Webb

(57) **CLAIM**

The ornamental design for a personal electronic device carrier, as shown and described.

DESCRIPTION

FIG. 1 is a front elevational view of a personal electronic device carrier showing my new design;
 FIG. 2 is a rear elevation view thereof;
 FIG. 3 is a side elevation view thereof;
 FIG. 4 is a side perspective view thereof as used;
 FIG. 5 is a top plan view thereof; and,
 FIG. 6 is a bottom plan view thereof.
